CLAIM

The ornamental design for a dosing scale, as shown and described.

DESCRIPTION

FIG. 1 is a top perspective view embodying the inventive design;

FIG. 2 is a front view thereof;

FIG. 3 is a right side thereof, with the left side being a mirror image of the right side;

FIG. 4 is a rear view thereof;

FIG. 5 is a top view thereof; and,

FIG. 6 is a bottom view thereof.

The broken lines are directed to environment and form no part of the claimed design.
